Primary Examiner — Michael A. Pratt

(74) *Attorney, Agent, or Firm* — Kaplan Breyer Schwarz,
LLP

(57) **CLAIM**

The ornamental design for the rifle as shown and described.

DESCRIPTION

FIG. 1 is an isometric view of a rifle showing my design.

FIG. 2 is front elevation view of the rifle of FIG. 1.

FIG. 3 is rear elevation view of the rifle of FIG. 1.

FIG. 4 is left side elevation view of the rifle of FIG. 1.

FIG. 5 is right side elevation view of the rifle of FIG. 1.

FIG. 6 is top plan view of the rifle of FIG. 1.

FIG. 7 is bottom plan view of the rifle of FIG. 1.

FIG. 8 is an enlarged isometric view of the rifle of FIG. 1, taken at the callout "8" of FIG. 1.

FIG. 9 is an enlarged front plan view of the rifle of FIG. 1, taken at the callout "9" of FIG. 2.

FIG. 10 is an enlarged left side elevation view of the rifle of FIG. 1, taken at the callout "10" of FIG. 4.

FIG. 11 is an enlarged right side elevation view of the rifle of FIG. 1, taken at the callout "11" of FIG. 5; and,

FIG. 12 is an enlarged top plan view of the rifle of FIG. 1, taken at the callout "12" of FIG. 6.

1 Claim, 6 Drawing Sheets
